UNITED STATES PATENT OFFICE.

BENJAMIN F. NIXON AND JOHN SAYELS, OF WINNIPEG, CANADA.

DRINKING-WATER APPARATUS FOR RAILROAD-TRAINS.

1,268,603.

Specification of Letters Patent. Patented June 4, 1918.

Application filed June 8, 1916. Serial No. 102,557.

To all whom it may concern:

Be it known that we, BENJAMIN F. NIXON and JOHN SAYELS, citizens of the United States, residing at Winnipeg, in the Dominion of Canada, have invented certain new and useful Improvements in Drinking-Water Apparatus for Railroad-Trains, of which the following is a specification, reference being had therein to the accompanying drawing.

This invention relates to a drinking water apparatus for railroad trains and has for its principal object the production of a simple and efficient means for automatically forcing water to a convenient position from which it may be drawn for use.

Another object of this invention is the production of an ice water drinking apparatus for railroad trains wherein a coiled pipe is used through which the water will pass, this coiled pipe being covered with ice so as to allow the water to be cooled and in which compressed air is employed for forcing the water from the coiled pipe as desired.

With these and other objects in view this invention consists of certain novel combinations, constructions, and arrangements of parts as will be hereinafter fully described and claimed.

In the accompanying drawings:

Figure 1 is a side elevation of the ice water filter for railroad trains, illustrating the construction in diagram.

Fig. 2 is a top plan view of the device.

Fig. 3 is a vertical section through the ice water filter, portions of the same being shown in elevation.

Fig. 4 is a section taken on the line 4—4 of Fig. 1.

Fig. 5 is a section taken on the line 5—5 of Fig. 1.

Fig. 6 is a sectional view through a certain valve used in connection with this device, through which air may be passed for blowing out the pipes when desired.

Referring to the accompanying drawings by numerals it will be seen that the device comprises a cooling drum 1 in which there is carried a coiled pipe 2. A short pipe 3 extends from the coiled pipe 2 and is provided with a cut-off valve 4 to which is connected an auxiliary filter 5. A pipe 6 extends from this filter 5 and carries the fountain 7 and the faucet 8. By means of the fountain it will be seen that a person may

have access to the water for drinking the same, while the faucet 8 will allow the water to be dispensed into any receiving receptacle desired. A bracket 9 is carried by the cooling drum 1 and is provided with a funnel 10 to which the drain pipe 11 is connected. Therefore, surplus water or the dripping from the faucet 8 will be caught by the funnel 10 and carried off by the drain pipe 11.

A short pipe 13 communicates with the interior of the drum 1, since it is carried by the bottom of the drum as clearly shown in Figs. 1 and 3. Since the drum 1 is adapted to carry a quantity of ice for the chilling of the coiled pipe 2 it is, of course, obvious that the ice will melt due to atmospheric conditions and consequently the water may be passed from the drum 1 by means of the pipe 13. A funnel 14 is carried so as to communicate with the drain pipe 15 and, therefore, the water from the melted ice may be easily conveyed to any desired place by passing through the drain pipe 15.

The main water tank 16 is adapted to be carried beneath the car, and is provided with the cover 17. It is, of course, obvious that this tank may be supported by any desired means, and it may be placed in any other desired position than under the car if it is found necessary to so move the tank. The filter 18 is positioned within the tank 16 and is provided with a number of apertures 19 so that the water within the tank 16 may be passed into the filter. This filter is adapted to be filled with a quantity of gravel, as indicated at 20 in Fig. 4, so that the water passing into the filter may be easily filtered. The water pipe 21 extends through the cover 17 and downwardly through the interior of the filter to a point adjacent the lower portions thereof, as shown in Fig. 4. Upon the upper end of this pipe 21 there is carried a blow valve 22 and from this blow valve 22 there extends a second water pipe 23 upon which the elbow 24 is positioned. The pipe 25 extends from the elbow 24 and is connected to the cut-off valve 26 from which extends a pipe 27 connected to the coiled pipe 2.

It will be seen that if it is desired to blow out the pipes 23 and 25 and the coiled pipe 2 an air hose from the main air pipe line upon the train may be connected to the threaded neck 28 of the valve 22. This valve 22 is provided with the pin 29 against which

the coiled spring 30 bears, while the opposite end of the coiled spring carries a cap 31. Therefore, it will be seen that this cap will normally close the opening through the neck 28 as clearly shown in Fig. 6. When, however, air is forced into the valve 22, the spring will be compressed so as to allow the air to pass through the valve and through the pipes 23 and 25 and 2 for efficiently 10 cleansing the same by blowing them out. It is, of course, obvious that a drain valve 32 is carried by the lower portions of the tank 16 so that when it is desired to drain or clean the tank the work may be easily accomplished by the opening of the drain valve 32. By referring to Figs. 1 and 2 it will also be seen that a threaded neck 33 is provided by means of which a hose may be attached to the water tank 16 for allowing 20 the water tank to be easily and quickly filled.

An air tank 34 is adapted to be carried beneath the car, not being deemed necessary to be herein disclosed, adjacent to the water tank 16. A pipe 35 is connected to this air tank 34, this pipe 35 being normally connected to the train air-line pipe, so that air may be easily forced into the tank 34 under pressure. A reducing valve 36 is connected to the pipe 37 extending from the air tank 34, and from this valve 36 there extends a pipe 38. It should, of course, be understood that this valve 36 may be constructed so as to reduce the pressure of the air to any desired pressure. A T-joint 39 is connected to the pipe 38 and has the auxiliary air pipe 40 connected thereto. This pipe 40 is connected to the air storage tank 41 by means of the elbow 42 and the pipe 43. It will be seen that as the air passes through the pipe 38 it will also pass through the pipe 40 and into the storage tank 41. A reducing valve 44 is connected to the T-joint by means of the pipe 45 and is constructed so as to further 45 reduce the pressure of the air before the same is passed into the tank 16 by means of the pipe 46.

When this device is in use the water is first passed into the water tank 16 through 50 the neck 33. Ice may then be placed within the cooling drum 1 so as to chill the coiled pipe 2. The air which is forced into the tank 34 will pass to the water tank 16 as well as to the storage tank 41. Therefore, the 55 pressure of the air within the water tank 16 will tend to force the water downwardly so as to pass from the tank 16 by means of

the pipe 21. The continued pressure of the air within the tank 16 will cause the water to pass through the gravel within the filter 60 18 and will continue to force the water through the pipes 23, 25 and the coiled pipe 2, as the water is dispensed through the fountain 4 and faucet 8. If the train pipe is cut off the air within the storage tank 41 65 will be of sufficient pressure to maintain the pressure within the tank 16 and, therefore, the flow of the water may be continued as long as there is water within the tank 16. It should, of course, be understood that the valve 36, while being a reduction valve will not allow the air from the storage tank 41 to re-pass therethrough when the train pipe is cut off. Furthermore, it is intended that the neck 33 be provided with any suitable 70 75 form of a check valve, not being deemed necessary to be herein disclosed so that although water will be forced into the tank 16 it will be impossible for the air compressed therein to escape through the neck 33.

From the foregoing description it will be seen that a very simple and efficient ice water filter has been provided for railroad trains which is so formed as to be connected to a single car, while the air therefor has to be 85 taken from the main air line of the train. It is, of course, obvious that the pipes as herein disclosed may be changed to any desired positions for it is not necessary to have the several tanks retained in their relative 90 positions as herein disclosed, as it is only necessary for the same to be connected as shown. Therefore, it will be seen that the ice water filter is in position and is assembled so as to efficiently operate whether the 95 car carrying the same is connected to a train or not, while the water may be efficiently cooled before it is dispensed for use.

What is claimed is:

In an apparatus of the class described, 100 the combination of a water-tank, a cooling-drum, a pipe connecting said water-tank and cooling-drum, an air-tank, a pipe connecting said water-tank and air-tank, a pair of reducing-valves mounted upon said last-mentioned pipe, a storage-tank, and a pipe connected to said storage-tank and connected to said last named pipe between said reducing-valves, substantially as shown and described.

In testimony whereof we hereunto affix 110 our signatures.

BENJAMIN F. NIXON.
JOHN SAYELS.
